BELT DRIVEN WIRE SPOOLER

William D. Pierson, Waterbury, Conn., assignor
to The Waterbury Farrel Foundry & Machine
Company, Waterbury, Conn., a corporation of
Connecticut

Application April 18, 1936, Serial No. 75,107

14 Claims. (Cl. 242—25)

This invention relates to improvements in wire spooling machines, and more particularly to a spooler attachment adapted to be applied to the end of a high speed heavy duty continuous wire-drawing machine.

One object of this invention is to provide a spooler attachment of the above nature in which the wire spool is adapted to be driven by means of a constant-speed endless belt, which is pressed into contact with the wire on the circumference of said spool, whereby the linear speed of the wire will be maintained uniform, irrespective of the spool diameter and amount of wire wound upon the spool.

15 A further object is to provide a spooler attachment of the above nature in which the winding spool is detachably journaled on a fixed horizontal axis and is driven by a substantially vertical endless belt running over a pair of pulleys mounted on horizontal axes at elevations above and below said spool, one of said pulleys being power-driven and mounted on a fixed shaft, while the other pulley is idle and is mounted on the free end of a swinging cradle pivoted on said

20 fixed shaft.

A further object is to provide a spooler attachment of the above nature in which the endless driving belt is normally urged against the winding spool with a substantially constant force by means of an adjustable compression spring or weight acting upon the swinging cradle.

25 A further object is to provide a spooler attachment of the above nature in which the endless belt may be readily swung out of contact with the wire on the winding spool by means of a handle member located on the free end of said cradle.

A further object is to provide a wire spooler attachment of the above nature having a latch member which is adapted to detachably snap over a hook located on a fixed part of the wire-drawing machine, said hook serving to hold the cradle and belt out of the way, leaving the operator free to employ both of his hands for manually removing the filled spool and replacing it with an unfilled spool.

30 A further object is to provide an alternative form of adjustable weight urged belt carrying cradle for winding the wire on the spool, in which the cradle is provided with a laterally extending curved arm at one end having a variable point of tangency with respect to a weight carrying cord passing over said curved arm.

35 A still further object is to provide a wire spooling device of the above nature which will be relatively simple in construction, inexpensive to

manufacture, easy to install and manipulate, compact, and very efficient and durable in use.

With these and other objects in view, there have been illustrated on the accompanying drawings two forms in which the invention may be conveniently embodied in practice.

In the drawings:

Fig. 1 represents a perspective view of the improved wire spooler unit as it appears when attached to one end of a high speed heavy duty wire-drawing machine.

Fig. 2 is a front end elevation of the spooler unit per se.

Fig. 3 is a top plan view of the same.

Fig. 4 is a side elevation of the same.

Fig. 5 is a fragmentary detail view of the compression spring supporting rod showing how it is connected to the cabinet of the wire-drawing machine.

Fig. 6 is a side view of a modified form of the invention in which the belt is pressed against the spool by the action of a weight connected by a cord to a curved arm extending laterally from the cradle.

Fig. 7 is an end view of the same.

Fig. 8 is a fragmentary detail view of a mechanism for locking the modified form of cradle out of the way when changing spools.

Fig. 9 is a fragmentary end view of the same.

This invention is similar to the light duty spooler attachment disclosed in a prior application filed by the same inventor on February 19, 1932, Serial No. 594,044, a patent for which was issued on February 4, 1936, No. 2,029,832.

Referring now to the drawings in which like reference numerals denote corresponding parts throughout the several views, the numeral 10 indicates generally a wire-drawing machine comprising a base pedestal 11 upon which is supported a heavy duty wire-drawing cabinet 12 in which are arranged two sets of upper and lower wire-drawing capstans 13. A pair of stepped holders 14 for a plurality of wire dies, not shown, are located between the capstans 13 of each set, as shown in Fig. 1, and it will be clear that in operation the wire 15 will be passed back and forth and around said capstans and through said dies successively until the desired reduction in diameter of the wire has been obtained. After being delivered from the wire-drawing cabinet 12, the wire 15 will pass around a final exterior drawing roll 16 mounted on the forward end of a spindle shaft 17 which is journaled in an extension box 18 connected to the right end or "exit" wall of the wire-drawing cabinet 12.

As the finished wire 15 leaves the final drawing roll 16, it will travel in an upwardly inclined direction to a guide pulley 19 carried on the free end of an overhead spring balanced arm 20, and thence downwardly to a winding spool 21. The overhead arm 20 is pivotally connected at its inner end to the outer end of a bracket member 22 made rigid to the adjacent side of the extension box 18 secured to the wiredrawing cabinet. The arm 20 is urged upwardly by means of a coiled spring 23 having tangential connection with a pair of grooved pulleys 24 and 25 journaled at opposite ends of the bracket member 22,—this feature of construction being well known in the art.

Winding spool mechanism

The winding spool 21 is provided with a pair of parallel end flanges 26 and 27, and is adapted to be removably journaled upon a pair of free running front and rear stud spindles 28 and 29, respectively. The rear stud spindle 29 is suitably journaled in a ball bearing race, not shown, contained within an enlarged adjustable hollow hub 30. The hub 30 is integrally connected to a flanged base 31 which in turn is adjustably attached to a raised pedestal 32 forming part of a main base 33 of the wire spooling unit. The above construction permits the hollow hub 30 to be adjusted along its longitudinal axis.

The forward stud spindle 28 is also journaled in a ball-bearing race, not shown, positioned in a hollow front movable hub 34. The hub 34 is slidably in a surrounding tubular casing 35 having an integral flanged flat base 36. The base 36 is adjustably connected with a front raised section 37 forming an integral part of the machine base 33. The upper section of the tubular casing 35 is longitudinally split at 38, and the opposite upper sides of said section 35 have integral upstanding lugs 39 and 40. A transverse binding screw stud 41 cooperatively passes through a hole in the lug 40 and engages in the lug 39 which is tapped to receive the threaded end of the stud 41. The stud 41 is provided on its right end, as viewed in Figs. 1 and 2, with an extension 42, upon which a clamping rod 43 is rigidly mounted. This construction permits the lugs 39 and 40 to be tightly drawn together to cause the side sections of the tubular casing 35 to clamp tightly upon the slidable hub 34 and hold it in adjusted position.

In order to move the hub 34 to the left, as viewed in Figs. 3 and 4, for the purpose of disengaging the forward spindle 28 from the spool 21, provision is made of a handle lever 44 fulcrummed in a bifurcated bracket 45 extending to the left from the flanged base 36 of said casing 35. The left end of the movable hub 34 is integrally formed with a pair of spaced lugs 46 connected to the handle lever 44 by a transverse pivot pin 47.

Belt driving mechanism

The vertical endless belt 48 for driving the winding spool 21 is preferably constructed of canvas or similar material, and is arranged so that its right-hand course, as viewed in Fig. 1, is adapted to contact with the wire 15 being wound on said spool 21. The belt 48 is mounted to travel around a pair of broad flangeless pulleys 49 and 50 which are journaled in the opposite forked ends 51 and 52, respectively, of a swinging cradle 53 normally located in a vertical position.

The lower pulley 50 is driven by means of a

driving shaft 54, upon which it is mounted, said shaft 54 also forming a fulcrum for the cradle 53. The front end of the driving shaft 54 is suitably journaled in a bearing hub 55 integrally formed on a horizontal bracket 55a (Fig. 2) secured to the raised section 37. The rear end of the driving shaft 54 is journaled in a reducing gear box 56 located adjacent the rear corner of the main base 33 at the right, as shown in Fig. 3. The gear box 56 receives power through an exterior pulley sheave 57 which is adapted to be connected by means of a belt 58 to a source of power, such as a motor 59, located in the hollow base pedestal 11 of the wire machine 10, (see Fig. 1).

The fixed lower end 52 of the swinging cradle 53 is provided with a pair of integral hollow hubs 60 and 61 containing ball bearings, not shown, which are journaled upon the rotating drive shaft 54, as best shown in Figs. 3 and 4.

In order to take up slack and permit adjustment of the sag in the driving belt 48, the uppermost pulley 49 (which is idle) is journaled upon a horizontal spindle shaft 62 held against rotation and supported at its extremities by a pair of eccentric bearing bushings 63 and 64 mounted within a pair of hollow hubs 65 and 66 formed integral with the forked upper end 51 of the swinging cradle 53. The bearing bushings 63 and 64 are each provided with a plurality of radial holes 63a and 64a for receiving a pin wrench whenever it is desired to manually twist said bushings 63 and 64 in their respective hubs 65 and 66 for varying the distance between the two pulleys 49 and 50. The tension of the driving belt 48 may thus be adjusted as desired.

To cause the endless belt 48 to press against the peripheral surface of the wire 15 being wound on the spool 21 with a substantially constant pressure, provision is made of a horizontal longitudinal rod 67 having a forked yoke 68 fixed to its right-hand end adjacent the cradle 53, as viewed in Fig. 1. The forked yoke 68 is pivoted to the opposite sides of the upper forked end 51 of the cradle 53 by means of a pair of lateral trunnions 69 engaging therein. The opposite or left-hand end 69a of the horizontal rod 67, as seen in Fig. 1, is slidably fitted within a swiveled bearing block 70 connected to the front wall of the wiredrawing machine pedestal 11 (see Figs. 1 and 5).

Surrounding the rod 67 is a relatively strong elongated helical spring 71 having its left end engaging the block 70 while its right end abuts against an adjustable slidable collar 72 secured to the rod 67, as by a set screw 72a. The swinging motion of the cradle member 53 toward the winding spool 21 is limited by means of an adjustable stop collar 73 slidably mounted on the rod 67 at the left of the bearing block 70.

It will be obvious from the above construction that as a winding spool 21 progressively fills up with wire, the cradle 53 will be swung counter-clockwise away from the full line vertical position, shown in Figs. 1 and 2, about its pivoting axis or shaft 54. This motion will increase the compression in the spring 71 somewhat, but due to the fact that the center of gravity of the cradle 53 is at the same time moved toward the left, the weight of the inclined cradle and pulleys supported thereon will exert a progressively increasing counter-clockwise force, the effect of which will substantially counter-balance that of the clockwise force due to the spring 71. The pressure of the belt 48 upon the

spool 21 will therefore remain practically constant at all times.

Such a constant pressure is desirable in order to produce a uniform winding speed of the wire upon the spool 21 so as to prevent slippage between the spool and the belt. A uniform winding speed is also essential to the proper operation and efficiency of the wiredrawing machine from which the wire is taken. The maintaining of a substantially uniform pressure of the belt upon the wire being spooled also assists in laying the wire more uniformly upon the spool, and thus prevents sticking of the wire and facilitates the unwinding of the wire from the spool during later use.

Moreover, by means of the present invention, the maximum speed of the wiredrawing may be maintained throughout the entire time of spooling, thus producing the greatest possible production from the machine.

In order to hold the driving belt 48 in inoperative position out of contact with the wire on the spool 21, as when it is desired to change spools, the innermost hollow hub 66 at the top 25 of the cradle is formed with an integral upwardly projecting boss 74 carrying a rigid upwardly projecting handle grip 75. Extending rearwardly from the handle grip 75 is an upwardly yieldable hooked latch member 78 which 30 is adapted to snap over an L-shaped horizontal rigid catch hook 79 attached to the adjacent wall of the extension box 18 (see Figs. 1 and 2). The latch member 78 is provided with an integral upwardly extending releasing movable gripping arm 80 held in spaced relation from the rigid handle grip 75 by means of a small interposed spring 81. The outer free end of the latch member 78 is provided with a cam-shaped nose 82 which is adapted to automatically snap 35 over the hook 79 by the action of the spring 81 when the cradle 53 is manually forced rearwardly by means of the handle 75. To release the latch 78 from the catch hook 79, it is only necessary to grasp the rigid handle 75 and manually force the movable releasing arm 80 to the right against the handle grip 75. The spring 78 will then be allowed to move the cradle 53 to its normal vertical operating position.

Belt traversing mechanism

In order to cause the belt 48 to be slowly reciprocated laterally between the spool flanges 26 and 27, and across the surfaces of the pulleys 49 and 50 for preventing "tracking" and keeping said belt clean, provision is made of a pair of upwardly inclined fingers 83 and 84 (see Fig. 2) straddling the left-hand course of said belt 48 and having their lower ends adjustably secured to a square horizontal traversing bar 85 located at the bottom of the cradle 53 (see Figs. 2 and 3). The ends of the traversing bar 85 are slidably journaled in a pair of square bosses 86 and 87 formed integral with the front bracket 55a and a small supporting bracket 88, respectively.

The reciprocating motion of the traversing bar 85 is produced by means of a small eccentric crank cylinder 89 (Fig. 3) secured to one end of a transverse shaft 90 and connected 70 with said bar 85 by a pitman link 91. The transverse shaft 90 is provided on its forward end with a pulley 92 driven by a belt 93 from a small driving pulley 94 located on the outside of the gear box 95. Power is supplied to the 75 gear box 95 from a large exterior cone pulley

96, which is driven by a belt 97 running over a smaller cone pulley 98 secured to the end of the motor-driven driving shaft 54 adjacent the sheave 57.

Wire traversing mechanism

In order to cause the wire 15 to be wound upon the spool 21 evenly in successive layers, provision is made of a pair of slightly spaced parallel downwardly inclined guide fingers 99, 10 between which the wire 15 passes on its way to the spool 21. The guide fingers 99 are secured at their upper ends to an angular holder block 100, which in turn is pivotally carried on the lower end of an adjustable clamping chock 101 15 mounted to slide upon a horizontal rectangular traversing bar 102. The traversing bar 102 is supported in an elevated position above the spool 21 by a pair of brackets 103 and 104, the bracket 103 being secured at the top of the hollow hub 20 30 30 while the bracket 104 is mounted on the top of the gear box 95.

The reciprocating movement of the bar 102 is produced by an upwardly extending oscillating lever 105 connected to said bar 102 by a pin 23 100 which is carried by a sliding plate (not shown) located in an elongated slot 105a provided in the upper end of said lever 105. The lever 105 is supported by a bracket 107 rigidly attached to the rear wall of the gear box 95, 30 and the fulcrum (not shown) of said lever 105 is adapted to be vertically adjusted by any well known means, whereby the stroke of the bar 102 may be varied as desired. The lever 105 is 35 swung back and forth about its adjustable 35 fulcrum by suitable means, not shown, in said gear box 95, said means being similar to that disclosed in the prior Patent 2,029,832 previously referred to.

Spool runway

In order to permit the easy removal of the heavy spool 24 after it has been filled with wire, without having to manually lift the same, provision is made of a platform 108 located a short 45 distance below the flanges 26 and 27 of the winding spool 21, as best shown in Fig. 4. A horizontal hinge rod 109 is supported by forwardly extending hinge lugs 109a at the upper edge of the platform 108, and serves as a pivot 50 for the upper ends of a pair of inclined laterally adjustable runways 110 and 111 leading down to the floor. The runways 110 and 111 are provided with outside raised guide flanges 112 and 113, respectively (see Figs. 3 and 4).

This construction is fully described in my previous Patent No. 1,874,206, dated August 30, 1932.

Operation

In the operation of replacing a filled wire spool 60 with an empty spool, it will only be necessary for the operator to grasp the fixed handle grip rod 75 of the cradle 53 and push the latter away from the spool as far as it will go. This will cause the cam-shaped nose 82 of the spring- 65 pressed latch 78 to snap over the catch hook 79 and automatically lock the latch member 73 thereon. The sliding hollow bearing hub 34 for the left-hand stud spindle 28 will next be loosened within the surrounding casing 35 by 70 manually swinging the inclined clamping rod 43 in the proper direction to turn the binding screw stud 41 and spread apart the sides of the upper split section 38 of said casing. The operator will next grip the lever 44 and swing it in 75

- a counter-clockwise direction, as viewed in Fig. 4, thereby moving the sliding hub 34 and its free running spindle 28 to the left out of engagement with the spool 21. This will release the spool 5 and permit it to drop directly upon the platform 108 therebelow. The spool 21 may then be readily taken out of the machine without lifting, by pulling it forwardly, causing it to roll down the runways 110 and 111 to the floor.
- 10 To insert an empty spool, the above operations will be reversed, and the driving belt 48 may be again brought into contact with the wire on the spool 21 by squeezing the releasing handle 80 of the latch member 78 against the handle grip 75, 15 thus releasing the cradle 53 which may then be allowed to swing to the right by the action of the spring 71 into its normal spool winding position.

Modified form

- 20 Figs. 6 to 9 inclusive illustrate a modified form 25 of mechanism for permitting the weight of the cradle and associated parts to be counter-balanced, and the pressure with which the belt will engage the wire on the spool to be accurately 30 adjusted, whereby a constant pressure of any desired amount may be maintained.

In this form of the invention the cradle 114 will be pivoted at its upper end upon a horizontal 35 drive shaft 115 mounted in a pair of enlarged hubs 116 and 117 located upon the top of a pair of hollow standards 118 and 119 resting upon the floor. The driving shaft 115 is adapted to receive power for driving an upper smooth pulley 120 from any suitable source, not shown, said pulley having an endless belt 121 passing thereover, which in turn drives an idle lower smooth pulley 122 which is loosely journaled on a horizontal shaft 123 mounted in the bottom free 40 end of the cradle 114. A flanged winding spool 124 is provided in this form with a central fixed shaft 125 journaled in a pair of fixed pedestals 126 in a manner similar to the members 32 and 37 disclosed in the first form of the invention, 45 only one of such pedestals 126 being herein shown. The hollow standard 118, as clearly shown in Fig. 6, is provided at its upper end with a vertical side bracket 127, upon the upper end of which is a horizontal forwardly-extending bracket 128 carrying a small grooved pulley 129.

The upper end of the cradle 114 is provided with a U-shaped yoke member 130, from the left-hand end of which extends a curved bell-crank arm 131, having an upwardly convex edge 55 132. A cord-holding pin 133 extends laterally from the extremity of said bell-crank arm 131.

In order to apply a variable force for counter-balancing the variable pressure exerted by the belt 121 upon the wire being spooled, a cord 134 60 is connected to the pin 133 and passes over the curved edge of the bell-crank arm, to which it is tangent, around a pulley 129, and then down into the hollow standard 118 through a suitable aperture in the upper end thereof. The lower 65 end of the cord 134 is connected to an eye 135 formed on the upper end of a rod 136, the bottom of which is threaded for receiving a nut 137 and a disc 138, upon which is supported a plurality of cylindrical weights 139.

70 The crank arm 131 is so shaped that as the cradle swings downwardly toward a vertical position as the spool fills up with wire, the point of tangency of the cord 134 upon said crank arm 132 will change in such a manner that the 75 constantly diminishing force due to the weight of

the cradle and associated parts acting in a clockwise direction around the fulcrum 115, and in opposition to the force of the weights 139, will be accompanied by the progressive shortening of the moment arm of the weights 139 due to the inward movement of the point of tangency of the cord 134 on said crank arm 131. This will result in a substantially constant pressure of the belt upon the spool.

It will be understood that any desired additional weights may be placed upon the disc 138 over and above that required to exactly counter-balance the weight of the cradle and associated parts, so as to adjust the pressure of the belt 121 upon the spool to any desired amount.

In order to permit the cradle to be temporarily held out of the way when changing spools, provision is made in the boss 117 of the right-hand standard 119 (see Figs. 7, 8 and 9) of a slidably spring-pressed locking bolt 140 having an elongated cylindrical head 141 urged at all times toward the yoke member 130, and adapted to engage in a socket 142 formed in said yoke member when the cradle has been swung rearwardly to a predetermined point. For permitting the locking bolt 140 to be manually withdrawn from the socket 142 and allowed to swing back into normal operating position, provision is made of a knurled control knob 143 located on the opposite end of said rod from the head 141. The bolt 140 carries a transverse pin 144 normally seated on the outer surface of the standard 119. When the knob 143 is turned 90 degrees in either direction, the pin 144 will engage in a depressed groove 145 in a raised section of the standard. 30 As will be understood, the locking bolt 140 will thus be permitted to slide to the left and automatically engage in the socket 142 when the cradle is manually swung to the left from the position shown in Fig. 6.

For the purpose of providing additional pressure of the cradle belt upon the wire being spooled, the yoke member 130 at the top of the cradle 114 has an upwardly extending detachable square rod 146 screwed into its upper end, upon 45 which is mounted an apertured rectangular sliding weight 147. The weight 147 may be adjusted up or down the length of the rod 146, and is adapted to be securely held at any desired adjusted position by means of a set screw 148.

While there have been disclosed in this specification two forms in which the invention may be embodied, it is to be understood that these forms are shown for the purpose of illustration only, and that the invention is not to be limited to the specific disclosures but may be modified and embodied in various other forms without departing from its spirit. In short, the invention includes all the modifications and embodiments coming within the scope of the following 55 claims.

Having thus fully described the invention, what is claimed as new, and for which it is desired to secure Letters Patent, is:

1. In a wire spooler, a support, a winding spool pivoted on a horizontal axis in said support, a substantially vertical inclined swinging cradle carrying pulleys at its opposite ends pivotally mounted on said support, an endless belt running at constant speed on said pulleys and having one course thereof engaging the wire being spooled, a spring-pressed horizontal rod connected with said cradle to urge it toward said spool, the spring pressure on said rod being progres- 70 75 75

sively increased as the cradle swings outwardly due to the filling up of the spool with wire whereby the counterforce due to the weight of the cradle and associated parts will be counterbalanced.

2. In a wire spooler, a support, a winding spool pivoted on a horizontal axis in said support, a substantially vertical inclined swinging cradle carrying pulleys at its opposite ends pivotally

10 mounted on said support, an endless belt running at constant speed on said pulleys and having one course thereof engaging the wire being spooled, spring means to urge said cradle toward said spool, the compression of said spring being automatically

15 progressively increased to substantially balance the gradual increase of counterforce due to the weight of the cradle and associated parts as the cradle swings away from the axis of the spool due to the filling up of the spool with

20 wire.

3. In a wire spooler, a support, a winding spool pivoted on a horizontal axis in said support, a substantially vertical inclined swinging cradle carrying pulleys at its opposite ends pivotally

25 mounted on said support on a fulcrum located below said spool, an endless belt running at constant speed on said pulleys and having one course thereof engaging the wire being spooled, means to urge said cradle toward said spool with a

30 progressively increasing force to substantially balance the gradual increase of counterforce due to weight of the cradle and associated parts as the cradle swings outwardly due to the filling up of the spool with wire.

35 4. In a wire spooler, a support, a winding spool pivoted on a horizontal axis in said support, a substantially vertical inclined swinging cradle carrying pulleys at its opposite ends pivotally mounted on said support, an endless belt running

40 at constant speed on said pulleys and having one course thereof engaging the wire being spooled, and adjustable means for exerting a progressively increasing force acting in the direction of spool to substantially balance the gradual increase of

45 force due to weight of the cradle and associated parts as the cradle swings outwardly due to the filling up of the spool with wire.

5. In a wire spooler, a support, a winding spool journaled in said support on a horizontal axis,

50 a substantially vertical inclined swinging cradle carrying pulleys at its opposite ends over which travels an endless belt running at constant speed for engaging the periphery of the wire on said spool, a substantially horizontal rod having pivotal connection at one end to said cradle, the other end of said rod being slidably mounted in a block having a swivel connection with said support, and a coiled spring on said rod engaging

55 said swiveled block at one end and fixed at its other end to said rod, the compression in said

60 spring being automatically increased progressively as the cradle swings away from the axis of the spool as the latter fills up to substantially counterbalance the gradual increase of force due to

65 the weight of the cradle and associated parts acting in the opposite direction.

6. In a wire spooler, a support, a winding spool journaled in said support on a horizontal axis, a substantially vertical inclined swinging cradle carrying pulleys at its opposite ends over which

70 travels an endless belt running at constant speed for engaging the periphery of the wire on said spool, a laterally extending rod having pivotal connection at one end to said cradle, the other

end of said rod being slidably mounted in a block having a swivel connection with said support, and a coiled spring on said rod engaging said swiveled block at one end, the compression in said spring being automatically increased progressively as the cradle swings away from the axis of the spool as the latter fills up to substantially counterbalance the gradual increase of force due to the weight of the cradle and associated parts acting in the opposite direction.

7. In a wire spooler, a support, a winding spool journaled in said support on a horizontal axis, a substantially vertical inclined swinging cradle carrying pulleys at its opposite ends over which

15 travels an endless belt running at constant speed for engaging the periphery of the wire on said spool, a laterally extending rod having pivotal connections at one end to said cradle, the other end of said rod being slidably mounted in a block

20 having a swivel connection with said support, a coiled spring on said rod engaging said swiveled block at one end and fixed at its other end to said rod, and a stop member on said rod beyond

25 said swiveled block to limit the movement of said belt toward said spool, the compression in said spring being automatically increased progressively as the cradle swings away from the axis of the spool as the latter fills up to substantially counterbalance the gradual increase of force due to the weight of the cradle and associated parts

30 acting in the opposite direction.

8. In a wire spooler, a support, a winding spool journaled on a horizontal axis in said support, a substantially vertical inclined cradle pivoted to

35 said support, a driven pulley and an idle pulley carried at opposite ends of said cradle, an endless belt running at constant speed on said pulleys, a hook on said support, and a spring catch on the

40 free end of said cradle in alignment with said hook to cause said latch to become automatically engaged with said hook when said cradle is manually pushed away from the spool so as to permit the operator to have both hands free when

55 changing spools.

9. In a wire spooler, a support, a winding spool 45 journaled on a horizontal axis in said support, a substantially vertical inclined cradle pivoted to

50 said support, a driven pulley and an idle pulley carried at opposite ends of said cradle, an endless belt running at constant speed on said pulleys, a hook on said support and a spring-pressed

55 manually releasable catch on the free end of said cradle in alignment with said hook to cause said cradle to become automatically latched out of the way from said spool when said cradle is manually moved away from said spool so as to permit the operator to have both hands free when

70 changing spools.

10. In a wire spooling machine a support, a horizontal winding spool, a constant speed vertically driven endless belt having contacting engagement with the wire being wound on said

60 spool, a swinging cradle pivoted on a fixed axis below and at one side of the axis of said spool and normally positioned in a substantially vertical

65 inclined position, a driving pulley and an idler pulley for supporting said endless belt mounted on the fixed and free ends of said swinging cradle respectively, a substantially horizontal rod connected at one end to the upper free end of said

70 cradle and slidably supported at its opposite end, a helical spring surrounding said rod and urging the belt toward said winding spool, and latch means on the upper end of said cradle for detachable engagement with said support for hold-

75

ing said belt out of contact with said spool to permit exchange of spools.

11. In a wire spooling machine, a support, a winding spool mounted on a horizontal axis in said support, a driving shaft mounted in said support below and laterally spaced from said spool, a substantially vertical inclined swinging cradle member pivoted at its lower end on said driving shaft, a driving pulley fixed upon said driving shaft, an idle pulley mounted on the upper free end of said cradle member, an endless belt traveling around said pulleys and driven at constant speed by said driving pulley, spring means for urging said cradle and belt toward said spool to frictionally engage the wire being wound on the surface thereof, the increasing force due to gravity acting away from said spool due to the swinging of said cradle as the spool fills with wire serving to substantially balance the increasing compression of said spring acting toward said spool, whereby a substantially uniform belt pressure upon said spool will be maintained.

12. In combination with a wiredrawing machine having a wiredrawing roll for pulling the drawn wire through the final die, a freely rotatable spool to which the drawn wire is directed to be wound thereon, mechanism for winding the wire on said spool at constant speed including a vertically disposed endless belt adapted to engage the wire being wound on the spool, a vertically disposed cradle bracket pivoted at one end to swing toward and away from said spool, a pulley at each end of said bracket and about which said belt is disposed, one of said pulleys being driven at constant speed, and means to maintain a substantially constant and uniform pressure of the belt upon the spool as the wire is being wound thereon including a compression spring arranged to urge the bracket toward the spool, said spring serving to counterbalance the weight of the bracket as the latter swings away from said spool due to the increased diameter of the spool caused by wire being wound thereon.

13. In combination with a wiredrawing machine including a series of dies, a drawing roll by which the wire is pulled through the last dies,

a freely rotatable spool for winding the wire leading from said roll, mechanism for spooling the wire at constant speed including a vertically disposed endless belt engaging the wire being wound on said spool, a vertically disposed cradle bracket pivoted at one end to swing toward and away from said spool, a pulley at each end of said bracket and about which said belt is disposed, one of said pulleys being driven at constant speed, the axes of said pulleys being in substantial vertical alignment when the belt is in engagement with an empty spool, a plane passing through said axes being substantially parallel to the horizontal axis of said spool, and means to maintain a substantially constant and uniform pressure of the belt upon the wire being spooled, including a compression spring, said spring acting to urge the bracket toward the spool to balance the counterforce due to said bracket as the latter swings out of the vertical away from said spool.

14. In combination with a wiredrawing machine having a wiredrawing roll from which the drawn wire leads, a freely rotatable spool to which the drawn wire is directed to be wound thereon, mechanism to wind said wire on said spool at constant speed including a vertically disposed endless belt adapted to engage the wire being wound on said spool, a vertically disposed cradle bracket pivoted at one end to swing toward and away from said spool, a pulley at each end of said bracket and about which said belt is disposed, one of said pulleys being driven at constant speed, means to maintain a substantially constant and uniform pressure of the belt upon the spool as wire is being wound thereon including a compression spring arranged to urge the bracket toward the spool, said spring serving to counterbalance the force of the bracket acting away from said spool as said bracket swings away from the axis of said spool due to the increasing diameter thereof caused by wire being wound thereon, and a releasable catch on said bracket adapted to engage a stationary part of said machine to hold said bracket away from said spool when it is swung into such position as to dispose said belt out of contact with said spool.

WILLIAM D. PIERSON.

CERTIFICATE OF CORRECTION.

Patent No. 2,141,934.

December 27, 1938.

WILLIAM D. PIERSON.

It is hereby certified that error appears in the printed specification of the above numbered patent requiring correction as follows: Page 5, first column, line 43, claim 4, before the word "spool" insert said; and second column, line 18, claim 7, for "connections" read connection; line 59, claim 10, after "machine" insert a comma; and that the said Letters Patent should be read with this correction therein that the same may conform to the record of the case in the Patent Office.

Signed and sealed this 7th day of February, A. D. 1939.

Henry Van Arsdale.

(Seal)

Acting Commissioner of Patents.
